DENMARK.

APPARATUS FOR BLOWING OUT SOOT IN BOILER TUBES.

1,416,708.

Specification of Letters Patent. Patented May 23, 1922.

Application filed July 8, 1918. Serial No. 243,936.

To all whom it may concern:

Be it known that we, ERNEST FREDERIK CARL HAGEDORN and HANS PETER HANSEN, subjects of the King of Denmark, and residents of Helsingør, in the Kingdom of Denmark, have invented certain new and useful Apparatus for Blowing Out Soot in Boiler Tubes, of which the following is a specification.

10 Our invention relates to an apparatus for blowing out soot in boiler tubes by means of a movable steam-spout for injecting a jet of steam into the mouths of the tubes, the said spout being placed in one of the boiler tubes, and adapted to be shifted into the combustion-chamber behind the tubes, and adjusted to form any suitable angle with its original position, thus being enabled to clean the boiler tubes, and the combustion-chamber itself.

Our invention is illustrated in the accompanying drawings in which:

Fig. 1 shows the apparatus in a vertical longitudinal section;

25 Fig. 2 the same in the corresponding horizontal section;

Fig. 3 the same in cross-section by the line 3—3 in Fig. 1;

30 Fig. 4 the apparatus constructed in a different manner;

Fig. 5 a fragment of the same;

Fig. 6 is a detail of a third modification;

Fig. 7 a fragment of a fourth; and

35 Figs. 8 and 9 a detail of a fifth modification, in end-view and section.

In one of the central boiler tubes 1 is fixed a bushing 2, carrying a rim 3. In the bushing 2 is movably inserted a tube shaped casing 4 carrying at its rear end, entering 40 the combustion-chamber 5, a cover 6 for closing the boiler tube when the apparatus is in its resting position, its other end being connected with a crank-handle *b* for shifting and turning the casing 4 to get it into its active position as shown in the drawing, or 45 to make it retire into the boiler tube 1, which is itself out of action. In a hollow space 7 of the casing 4 is on a screw-rod 8 a tooth-wheel 9 arranged, which by inserting the 50 casing into the boiler tube gets in gear with the rim 3. The screw-rod 8 is connected with a rack 10.

The casing 4 surrounds the steam-tube 11, which at the outer end in a well known manner is connected with the steam supply, and

at the inner with a cock-case 12 communicating with the spout 13, the length of which corresponds to the breadth of the combustion-chamber. The cock-case has on its surface teeth 14 adapted to be acted upon by the 60 rack 10.

When, the casing 4 is being pushed into the combustion-chamber, the steam-spout 13 is in the position shown in full lines, and the crank-handle is turned, the rack 10 will be 65 carried to the right in the drawing, by the movement of the screw-rod 8 effected by the gearing 3—9, as far as a stop-knot 15 will allow, and thereby act upon the teeth 14, thus lifting the steam-spout slowly into the 70 working position as shown at 13^a in Fig. 1. In this manner the spout 13 by degrees is directed towards the mouths of the boiler tubes, moving as it does between its extreme 75 positions during the continued rotation of the casing 4 and simultaneously turning around the longitudinal axis of the casing till it is carried back to its original position, and the casing is drawn within the boiler tube.

80 In the modification shown in Figs. 4 and 5 the steam enters in the direction of the arrow and streams through apertures *c* into the steam-tube 11, which ends in a hollow space 16 arranged in the wall of the casing 4, and communicating, through a cock-plug 17 removably fixed in the casing with the steam-spout 13. The spout can move around the 85 cock-plug 17 and is formed so as to be able to spread or gather the steam-jet. The cover 90 6 is made to unscrew.

95 In order that the apparatus may be used in boiler tubes so narrow that the bushing 2 cannot easily be applied, the screw-rod 8 is carried out through the handle crank *d* and connected with means for moving it, independent of the turning of the casing. The screw-end of the rod 8 may, as shown in Fig. 6, be carried into a guide 18 turningly connected with the casing 4 by a stuffing-box 19 and supplied with a fixed handle 20 for lifting and lowering the steam-spout whilst the casing 4 is turned by the handle *d*, and serves as steam-tube. As shown in Fig. 7, the screw-rod 8 is supplied with a square 21 100 in a guide to prevent it from turning and it may like the casing consist of two parts held together by screw-threads 22 and 23, allowing the outer part to be easily removed. The guide 18 may be supplied with an arm 110

24 which by pressing against an arm 25 on the smoke-chamber-door *e* moves the screw-rod 8, when the handle *d* is turned. By placing the arm 25 in the position 25 as shown by dotted lines in Fig. 7 only the casing 4 will be turned. In the modification of this detail, as shown in Figs. 8 and 9, the revolving guide 18 is held by a flange 26 and supplied with a tooth-wheel 27 engaging 10 with a smaller one 28 having a crank-handle 29. When the latter is gripped by the operator, while the casing is turned, the screw-rod 8 will be moved and the steam-spout raised or lowered.

15 The apparatus, which thus may be constructed in different ways without departing from the principle of this invention, need not to be built in one with the boiler-tube but may be removed after use, the projecting edges of the cover 6 being, however, abolished.

Having thus described our invention, we claim:

1. In an apparatus for blowing out soot 25 in boiler tubes, the combination of a tube-shaped casing closed at the rear end and adapted to be placed in a boiler tube, a steam-spout and a steam-tube placed in the said casing and communicating with the 30 steam supply, a cock-case having teeth and connecting the said steam-spout with the said steam-tube, a handle for turning the said casing, a rack acting upon the teeth of the said cock-case, a screw-rod connected

with the said rack, and a gearing for moving 35 the said screw-rod lengthwise, when said handle is turned, substantially as set forth.

2. In an apparatus for blowing out soot in boiler tubes, the combination of a tube-shaped casing adapted to be placed in a boiler tube, a threaded cap at the rear end of the said casing adapted to be unscrewed, a steam-spout, a steam-tube having apertures forming passages for the steam, a cock-case 40 connecting the said steam-spout with the said steam-tube, a cock-plug placed in the said cock-case and adapted to be removed, a groove arranged in the said casing and communicating with the said cock-plug, a handle for turning the said casing, means 45 forming a hollow space in the said casing, a tooth-wheel placed in the said hollow space, a screw-rod forming an axle for the said tooth-wheel, a guide for the said screw-rod, a bushing fixed in the said boiler tube 50 and having a rim engaging with the said tooth-wheel, and a rack connected with the said screw-rod and acting upon the teeth of the said cock-case, when said handle is turned, substantially as set forth.

60 In testimony whereof we affix our signatures in presence of two witnesses.

ERNST FREDERIK CARL HAGEDORN.
HANS PETER HANSEN.
